J. E. HARDY,
CONVERTIBLE TABLE,
APPLICATION FILED FEB. 9, 1920.

1,385,046.

Patented July 19, 1921.

Inventor:
John E. Hardy.

J. J. Geisler
by Atty.

UNITED STATES PATENT OFFICE.

JOHN E. HARDY, OF PORTLAND, OREGON.

CONVERTIBLE TABLE.

1,385,046.

Specification of Letters Patent.

Patented July 19, 1921.

Application filed February 9, 1920. Serial No. 357,352.

To all whom it may concern:

Be it known that I, JOHN E. HARDY, a citizen of the United States, and resident of Portland, county of Multnomah, State of Oregon, have invented a new and useful Improvement in Convertible Tables, of which the following is a specification.

The object of my invention is to provide a foldable camp table of which the body shall 10 constitute a cabinet or case arranged into compact box-like form for carrying about, being especially adapted for carrying on the running board of an automobile; and which furthermore shall be provided with a cover 15 to be placed over the top of the case when the table is folded together, and serving as a protection against the weather; and when the table is stood up for use this cover serves as a lower shelf, and incidentally serves to 20 hold the legs of the table rigid.

My invention further includes a novel and convenient arrangement of removable sides of the case-like body of my table; these sides constituting leaves which may be 25 firmly supported in abutment with the side edges of the case top, and when so arranged constitute lateral extensions of the table.

I attain this and other objects of my invention by means of the construction shown 30 in the accompanying drawings, in which—

Figure 1 is a perspective view of my device showing it arranged for use as a table;

Fig. 2 is a perspective view of my device showing it arranged in the form of a box 35 ready to be packed on the running board of an automobile;

Fig. 3 is a larger scaled transverse section showing details of construction;

Fig. 4 is a similar section taken on the 40 broken line 4 of Fig. 1; and

Fig. 5 is still another similar section taken on the broken line 5 of Fig. 1.

My table comprises a cabinet, or case-like body consisting of a bottom *a*, ends *b*, and 5 top *c*, and having open sides. Sides *d*, are movably secured in place by slotted struts *e* pivoted at their upper ends to the sides *d* and secured to the ends *b* of the case-like body by pins *f* bearing in the slots of the struts. Companion latch members *g* and *h* on the leaves *d* and ends *b* respectively form a medium for holding the sides securely in the open sides of the body.

Arms *i* are pivoted to the under side of the case-top *c*, and are adapted to be extended laterally from the case tops so as to

provide supports for the leaves *d*, and when so extended they project a substantial distance beyond the point of rotation of the leaves on said struts *e*, hence these arms support the sides *d* against rotating on the struts, and the latter, co-operatively, hold these leaves firmly down on said arms *i*; see Fig. 4.

The sides *d* are further made with dowels 65 *j*, and the top *c* has slots *k*, into which said dowels fit when the sides are arranged to close the open sides of the case. These dowels *j* also serve as a support for the sides *d* when arranged as leaves of the table 70 top.

Holes *l* are bored vertically in the ends *b*, and detachable table legs *m* having diverging feet are adapted to seat in these holes and form a rigid supporting medium for the 75 table when the latter is being used as such.

A flanged cover *n* is adapted to be placed over the top of the table body when the leaves *d* are arranged in the open sides of the latter as shown in Figs. 2 and 3, thus 80 the cover protects the top of the case from the weather when my table is folded together for carrying about.

Said cover *n* has transverse elongate slots *o* located in alinement with the holes or bores 85 *l* of the end pieces of the case thereby adapting the cover to be arranged as shown in Figs. 1 and 3, and when so arranged the cover *n* constitutes a lower shelf. At the same time the slotted ends of the cover *n* 90 engage and lock with said angular lower portions of the legs *m*, and in so doing hold the latter rigid, and prevent them from rotating in the bores *l* of the case ends.

When folded up into box form, as shown 95 in Fig. 2, my table may be used as a container for food, dishes, utensils, and other traveling equipment. When converted into the table form, as shown in Fig. 1, the devices will serve admirably as a table, provided with the additional facilities of the shelves formed by the bottom board *a* and inverted cover *n*.

Having thus described my invention I claim:

1. In a camp table, the combination of a case-like body, legs adapted for being removable fastened in the ends of the case the lower ends of the legs being bent at coincident angles, and a flanged cover adapted for 110 being placed on the top of said body and further adapted for being mounted on said

legs so as to form a shelf therewith, and at the same time to hold said legs rigid.

2. In a camp table the combination of a case-like body, the ends of the latter having 5 sockets, legs adapted for being removable inserted in said sockets the lower ends of the legs being bent at coincident angles, and a flanged cover adapted for being placed on the top of said body and further adapted 10 for being mounted on said legs so as to form a shelf therewith, and at the same time to hold said legs rigid.

3. In a camp table, the combination of a case-like body, the ends of the latter having 15 sockets, legs adapted for being removable inserted in said sockets the lower ends of the legs being bent at coincident angles and a flanged cover adapted for being placed on the top of said body and provided with transverse elongate slots at its ends for 20 receiving the angular lower portions of said legs, thereby holding the latter rigid and forming a shelf therewith.

JOHN E. HARDY.
